SEWING MACHINE

George Sauer, Berwyn, and Clarence C. Smith,
Chicago, Ill., assignors to Union Special Ma-
chine Company, Chicago, Ill., a corporation of
Illinois

Application February 5, 1938, Serial No. 188,836

9 Claims. (Cl. 112—256)

This invention relates to sewing machines; and it has reference more particularly to sewing machines of the type wherein the complementary stitch-forming and feeding mechanism is located below the work support and operated through a plurality of links, from rotary actuators on a revolving shaft. In the usual forms of such sewing machines, these rotary actuators are mounted upon or integrally formed on a horizontal shaft from which the needle derives its movements, said shaft being at a considerable height above the work support so that correspondingly long and relatively heavy link rods must be used to reach from said shaft to the complementary stitch-forming and feeding mechanism beneath the work support. Due to their length and weight, considerable vibration is set up by the momentum of the rods incident to their oscillation, as a result of which the speed of the machines is greatly limited.

Our invention has for one of its aims to obviate the above drawback, which objective we realize in practice as hereinafter more fully disclosed, through provision of a parallel countershaft at a level intermediate the needle-actuating shaft and the work support for operating the complementary stitch-forming and feeding mechanism, so that shorter, and hence lighter connecting links can be used, and through provision of rotary gears to connect the two shafts.

Another aim of our invention is to make it possible to utilize the gears in a structure such as outlined above as a pump to draw oil from a reservoir or sump for distribution to moving parts of the machine requiring lubrication, which objective we attain, as also hereinafter more fully set forth by suitably enclosing the gears and providing for conduction of the oil to and from the pump so formed.

Other objects and attendant advantages of this invention will appear from the following detailed description of the attached drawings, whereof

Fig. I is a plan view of a feed off the arm chain stitch sewing machine embodying the present improvements.

Fig. II is a view of the machine partly in side elevation and partly in longitudinal section.

Figs. III and IV are fragmentary detail sectional views taken as indicated respectively by the arrows III—III and IV—IV in Fig. I.

Fig. V is a fragmentary detail section taken as indicated by the arrows V—V in Fig. II.

Fig. VI is a fragmentary detail section taken as indicated by the arrows VI—VI in Figs. II and V.

Fig. VII is a detail section taken as indicated by the arrows VII—VII in Fig. II with a portion of the cover for the gear pump broken out.

Fig. VIII is a plan view of the work support of the machine with its covers removed.

Fig. IX is a longitudinal sectional view of the work support taken as indicated by the arrows IX—IX in Fig. VIII, showing the complementary stitch-forming and feeding mechanism; and

Fig. X is a cross section taken as indicated by the arrows X—X in Fig. IX.

The frame of the sewing machine herein illustrated for convenience of exemplifying our invention has a laterally-projecting longitudinal tubular portion 1, which is sustained at an elevation by an integrally formed bracket-like base 2. A neck 3 extending laterally from one end of the elevated frame portion 1, terminates in a head 4 which overreaches the corresponding free end 10 of a hollow work support in the form of an arm 5, said arm constituting a detachable part of the machine frame and being connected at its opposite end, by suitable fastening devices (not shown) to a hollow vertical frame portion 6 pendant from said longitudinal tubular portion. Guided for up and down movement in the head 4 is a bar 7 which carries a pair of needles 8 at its lower end, said bar being reciprocated through the medium of a pitman 9 from a balanced crank member 10 at the outer end of a shaft 11 journaled within said head. As shown in Fig. I, the shaft 11 extends at right angles to a longitudinal shaft 12 within the elevated tubular frame portion 1, from which longitudinal shaft it is driven through a pair of miter gears 13 and 14. From Fig. III, it will be observed that the shaft 11 is supported for rotation in spaced bearings 15, 16 within the neck 3 of the machine frame, and that said bearings and the miter gears 13, 14 are enclosed within a housing 17 at the interior of the neck, said housing having a removable lid 18. The parts in the neck 3 are accessible upon removal of a cover member shown at 3a. The shaft 12, which will hereinafter be referred to as the needle actuating shaft is journaled in suitably spaced bearings 18, 19, 20 and protrudes at the front end of the machine where it is provided with a combined hand and belt wheel 21 so that the machine may be operated either manually or by power. The bearings 18, 20 are set into partitions 22, 23, which extend crosswise of the elevated tubular portion 1 of the machine frame, the partition 23 being an upward continuation of the inner side wall 24 of the vertical frame portion 6. Also guided in the head 4 is a bar 25 whereto is affixed

40
45
50
55

at the lower end a presser foot 26. By means of a leaf spring which is shown end-on at 27 in Fig. II, the presser bar 25 is yieldingly depressed to hold down the material being sewed on the work arm 5 as required. The space 28 between the partitions 22, 23 is, in this instance, utilized as a chamber to house rotary take ups 29, 30 and tensions 31, 32 for the threads employed in the sewing, said chamber being closed at the top by a hinged lid 33.

The hollow of the work arm 5, see Figs. VI-VIII, is occupied by the complementary stitch-forming and feeding mechanism of the machine, which mechanism is shown as being of the construction described and claimed in a separate patent application Serial Number 188,837, filed by us concurrently herewith. Briefly, this mechanism includes a pair of complementary stitch-forming devices in the form of loopers 35 arranged to cooperate respectively with the needles 8. As shown, the loopers 35 are secured to the forward end of a shaft 36 which is journaled, with capacity for endwise shifting and for oscillation, in bearings 37, 38 and 39 within the work arm 5. The shaft 36 receives its endwise movements for communication of needle-avoiding movements to the loopers 35, through a link 40 which is pivotally connected at 41 to a collar 42 confined axially between a pair of fixed collars 43 on said shaft, and which has an adjustable connection at 45 with the pendant slotted extremity 46a of a double arm rocker 46 secured to a transverse rock shaft 47 within the work arm 5. The connection 45 is accessible for adjustment by removal of a screw plug 48 threaded laterally into one side of the work arm 5, see Fig. II. Oscillatory movements are imparted to the looper shaft 36 by connections later on explained, for communication of loop-taking movements to the loopers 35, through a crank arm 49 which is secured to the rear end of said shaft beyond the bearing 39. Mounted to rock about another transverse axis 50 within the work arm 5 is a longitudinally-extending sleeve 51 which serves as a guide for a rod 52 having a head 53 at its outer end whereon a feed dog 54 is mounted. The rod 52 is reciprocated axially within the sleeve 51 for impartation of horizontal to and fro movements to the feed dog 54 through a link 55 which has an adjustable connection at 56 with the slotted upward extremity 46b of the double arm rocker 46, said connection 56 being accessible for adjustment upon removal of another screw plug 57 at a level above the screw plug 48. The sleeve 51 is rocked to induce up and down or lift movements of the feed dog 54 through action upon a rearwardly projecting arm 58 on said sleeve by connections also later on explained.

The improvements which we have made for reducing vibration in a sewing machine of the above character to a minimum are as follows:

Disposed within the hollow of the vertical portion 6 of the machine frame at a level between the needle actuating shaft 12 and the work arm 5 is a parallel countershaft 60 whereof the ends are journaled in bearings 61 and 62 respectively set into the opposite side walls 24 and 63 of said frame portion 6. As shown the counter shaft 60 is driven from the needle actuating shaft 12 by a pair of intermeshing spur gears 65 and 66. Intermediate its bearings 61 and 62, the counter-shaft 60 is formed with rotary actuators or cranks 67, 68 and 69, which, through links 70, 71 and 72 extending downwardly within the hollow of the vertical frame portion 6 into the rear end

of the work arm 5, are respectively connected to the rearwardly projecting arm 58 of the sleeve 51, to a horizontal arm 73 of the rocker 46, and to the crank 49 at the rear end of the looper shaft 36. It is, of course, to be understood that the cranks 67-69 are so spaced angularly on the countershaft 60 as to insure properly timed action of the loopers 35 and of the feed dog 54 with respect to the movements of the needles 8. The construction just described obviously favors use of considerably shorter and therefore lighter connecting links as compared with connecting links which reach up to the needle actuating shaft as is the case in the usual forms of sewing machines of this class. It therefore follows that our improved sewing machine can be operated at higher speeds in view of the reduced weight and momentum of the links, with attainment of a correspondingly greater output of work from the machine.

In order that the gears 65, 66 may be utilized for the purpose of an oil pump, we have provided a conformative recess 75 in the inner face of the partition wall 24, into which recess said gears snugly fit; and have moreover closed said recess with a cover 76. This cover 76 is removably held in place by a tubular keeper 77 which has a threaded outer end portion engaged in a tapped hole 78 in the outer side wall 63 of the vertical frame portion 6. At its outer end, the keeper has a crosswise slot so that a screw driver can be used to remove or to tighten it. The amount of oil pumped is regulatable by means of a stem 79 which occupies the axial hollow of the keeper 77 and which has a threaded inner end engaging through a tapped hole 80 into the cover 76, see Figs. II, V and VI. At shown, the threaded end of the stem 79 projects into a by-pass recess 82 which is formed at the inside face of the cover 76 and which overlies the region of tangency of the gears 65, 66. As shown in Fig. II, the stem 79 is formed with a slot 79a at its outer end so that a screw driver can be used in adjusting it to vary the size of the by-pass 82 and thereby regulate the capacity of the pump. Upon detaching a closure plate 83 secured by screws, whereof one is shown at 84 in Fig. II, within the recess at the outer side of the wall 63 of the vertical frame portion 6, access may be had to the keeper 77 and to the stem 79 for the purposes of adjustment or removal. Also, upon detachment of the closure plate 83, the bearing 62 may be withdrawn from its receiving opening in the wall 63, said opening being large enough to allow of endwise withdrawal of the countershaft 60 after backing off the screw 85 by which the spur gear 66 is secured to said shaft. The hollow of the vertical frame portion 6 is accessible from above upon removal of the lid shown at 86 in Figs. I and II whereupon the pump cover 76 and the gears 65, 66 can be withdrawn subsequent to removal of the other parts as above described.

During the operation of the sewing machine, the pump formed by the gears 65, 66 draws oil through a tube 87 which connects into the suction or inlet side of said pump at 88 (Figs. VI and VII) from a reservoir or sump 89 formed at the rear end of the work arm 5 in line with the hollow of the vertical frame portion 6, the bottom of said work arm being inclined downwardly and rearwardly to drain toward said sump. In this connection, it is to be noted that the screw plug 48 (Fig. II) is well above the level of the oil in the sump 89 so that oil leakage from the machine and soiling of the work is precluded.

The oil lifted by the action of the pump from the sump 89 is delivered from the pressure or discharge side of said pump at 90 through a tube 91 which terminates above one of the rotary actuators 67—69 on the countershaft 60 and flows along said shaft, the excess dripping down onto the moving parts within the rear end of the work arm 5 and being finally collected in the sump. The distribution of the oil is enhanced by the rapid movement of the parts, which are thus all thoroughly and constantly lubricated. Some of this splashed oil moreover finds its way into the bearings 62 of the countershaft, and some of the oil circulated within the pump will seep into the bearing 61 as well as into the bearing 20 for the needle actuating shaft 12. Of course, if found desirable, branches may be connected into the pump discharge for delivery of oil to other parts of the machine. Leakage of oil outwardly past the bearing 61 of the countershaft 60 is prevented by a plug 92 forced into the opening for said bearing in the wall 24. The moving parts within the head 4 are lubricated by the splash of oil which is lifted from a small sump 93 in the bottom of said head by the action of a scoop 94 at the lower end of the pitman 9. The housing for the miter gears is similarly formed at the bottom with a sump 95 from which oil is carried up by said gears to lubricate the inner bearing 15 for the transverse shaft 11 as well as the bearings 18, 19 for the needle actuating shaft 12.

Our invention is not to be considered as limited to the precise details of construction herein specifically shown and described since various modifications may be made within the scope of the appended claims. Nor is its adaptation confined to the particular style of sewing machine chosen for convenience of illustration herein, since, it may be incorporated, with attainment of advantages in all respects equal to those hereinbefore pointed out, to flat bed and other types of sewing machines by resorting to changes within the province of mechanics skilled in the art.

Having thus described our invention, we claim:

1. In a sewing machine a work support; a needle; a needle-actuating shaft; complementary stitch-forming and feeding mechanism; a parallel shaft from which said mechanism is actuated; a pair of spur gears connecting the two shafts and enclosed for the purposes of a gear pump; a by-pass in the region of tangency of the gears; a supply reservoir from which the pump draws oil; means whereby the oil is conducted from the pump to moving parts of the machine; and means whereby the size of the by-pass can be varied to regulate the capacity of the pump.

2. In a sewing machine a work support; a needle; a needle-actuating shaft; complementary stitch-forming and feeding mechanism; a parallel shaft from which said mechanism is actuated; a pair of spur gears connecting the two shafts and enclosed for the purposes of a gear pump; a by-pass in the region of tangency of the gears; a supply reservoir from which the pump draws oil; means whereby the oil is conducted from the pump to moving parts of the machine; and a screw member adjustable into and out of the by-pass to vary the size of said by-pass and thereby regulate the capacity of the pump.

3. In a sewing machine, a frame providing a hollow work support; a hollow longitudinally-extending elevated portion above said support, 75

- and a hollow vertical portion connecting the arm and the work support; a needle-carrying bar guided for up and down movement in the elevated frame portion; complementary stitch-forming and feeding mechanism within the hollow of the work support; a horizontal shaft journaled within the vertical portion of the frame at a level between the needle shaft and the work support; a pair of intermeshing spur gears connecting the two shafts and confined within a cavity in the wall of the vertical connecting frame portion for the purposes of a gear pump; an oil reservoir within the hollow of the work support from which the gear pump draws oil; means whereby the oil is conducted from the gear pump to various moving parts of the machine; and means accessible from the exterior of the machine frame whereby the capacity of the pump may be regulated.
- 20 4. In a sewing machine, a frame providing a hollow work support; a hollow longitudinally-extending elevated portion above the work support, and a hollow vertical portion joining the work support and the elevated frame portion, one wall of the vertical frame portion being continued upwardly to form a partition across the hollow of the elevated frame portion; a needle-carrying bar guided for up and down movement in the elevated frame portion; complementary stitch-forming means and feeding mechanism within the hollow of the work support; a needle-actuating shaft extending longitudinally of the elevated frame portion and having a journal in the partition wall aforesaid; a parallel countershaft within the vertical frame portion from which the complementary stitch-forming and feeding mechanism is actuated, said countershaft having a journal in the partition wall; a pair of intermeshing spur gears connecting the two shafts enclosed within a hollow in the partition wall for the purposes of a gear pump; a reservoir within the hollow of the work arm from which the pump draws oil; and means whereby the oil is conducted from the pump to various moving parts of the machine.
- 45 5. In a sewing machine, a frame providing a hollow work support; a hollow longitudinally-extending elevated portion above the work support, and a hollow vertical portion joining the work support and the elevated frame portion, one wall of the vertical frame portion being continued upwardly to form a partition across the hollow of the elevated frame portion; a needle-carrying bar guided for up and down movement in the elevated portion of the frame; complementary stitch-forming and feeding mechanism within the hollow of the work support; a needle-actuating shaft extending longitudinally of the elevated portion of the frame and having a journal in the partition wall aforesaid; a parallel countershaft at a lower level within the vertical frame portion from which the complementary stitch-forming and feeding mechanism is actuated, said countershaft having a journal in the partition wall; a pair of intermeshing spur gears connecting the two shafts and fitting into a recess in the partition wall; a cover closing the recess to confine the gears for the purposes of a gear pump; a reservoir within the hollow of the work arm from which the gear pump draws oil; means whereby the oil is conducted from the gear pump to various moving parts of the machine; a tubular keeper bearing at one end upon the pump cover to hold it in place and secured at the other end within an opening in a

wall of the vertical frame portion opposite the partition wall; and means whereby the capacity of the pump may be regulated, including an adjustable stem which extends inward through the tubular keeper and which has its inner end threadedly engaged in a tapped hole in the gear cover and projecting into a by-pass at the region of tangency of the gears.

6. In a sewing machine, a frame providing a hollow work support, a hollow longitudinally extending elevated tubular portion above said support; and a hollow vertical portion joining the work support and the elevated frame portion; a needle-carrying bar guided for up and down movement in the elevated frame portion; complementary stitch-forming and feeding mechanism within the hollow of the work support; a needle-actuating shaft extending longitudinally of the hollow of the arm; a parallel countershaft within the machine frame at a level between the needle shaft and the work support; link rods extending downwardly within the vertical hollow of the machine frame from rotary actuators on the countershaft to operate the complementary stitch-forming and feeding mechanism within the work support; a pair of spur gears connecting the two shafts and enclosed within a cavity in the machine frame for the purposes of a gear pump; an oil sump in the bottom of the work support from which oil is drawn by the pump; and means whereby the oil is conducted from the pump for discharge from above upon the rotary actuators on the countershaft.

7. In a sewing machine, a frame including a component with a horizontal tubular portion having a needle head at one end and a hollow downwardly open depending portion at the other end, and a hollow horizontal work supporting component whereof one end communicates with the hollow depending portion of the first component and whereof the other end underreaches the needle head; needle operating mechanism on the head; a shaft from which the needle operating mechanism is operated extending lengthwise through the horizontal portion of the first frame component into the depending portion of the lat-

ter; feeding and complementary stitch-forming devices carried by the work supporting component of the frame; a second rotary shaft within the depending portion of the first frame component below and in parallel relation to the first shaft at a level intermediate the two components, from which the feeding and complementary stitch-forming devices are actuated; gearing connecting said shafts; housing means within said depending portion enclosing the gearing for the purpose of a pump to draw oil from an underlying sump; and means for conducting the oil from the pump to parts within the frame requiring lubrication.

8. In a sewing machine, a frame including a component with a horizontal tubular portion having a needle head at one end and a hollow downwardly open depending portion at the other end, and a hollow horizontal work supporting component whereof one end communicates with the hollow depending portion of the first component and whereof the other end underreaches the needle head; needle operating mechanism on the head; a shaft from which the needle operating mechanism is operated said shaft extending lengthwise through the horizontal portion of the first frame component into the depending portion of the latter; feeding and complementary stitch-forming devices carried by the work supporting component of the frame; a second rotary shaft within said depending portion of the first frame below and in parallel relation to the first shaft and at a level intermediate the two components, from which the feeding and complementary stitch-forming devices are actuated; gearing connecting said shafts; housing means within said depending portion enclosing the gearing for the purpose of a pump; an intake pipe leading from the sump to the pump and a discharge pipe leading from the pump to conduct oil to parts within the frame requiring lubrication.

9. A sewing machine according to claim 7, including means whereby the capacity of the pump may be regulated from the exterior of the frame.

GEORGE SAUER.
CLARENCE C. SMITH.
